UNITED STATES PATENT OFFICE.

ADOLPH WUNDER, OF NEW HAVEN, CONNECTICUT, ASSIGNOR TO SARGENT & CO., OF SAME PLACE.

DESIGN FOR DRAWER-PULL.

Specification forming part of Design No. 6,161, dated October 1, 1872.

CASE C.

To all whom it may concern:

Be it known that I, ADOLPH WUNDER, of New Haven, in the county of New Haven and State of Connecticut, have invented a new Design for Drawer-Pull; and I do hereby declare the following, when taken in connection with the accompanying drawing and the letters of reference marked thereon, to be a full, clear, and exact description of the same, and which said drawing constitutes part of this specification, and represents in—

Figure 1, a front view; and in Fig. 2, a top view.

This invention relates to a design for that class of drawer-pulls which are formed from cast metal in a box or shell form; and consists in the peculiar configuration and ornamentation, as shown in the accompanying illustrations, and as hereinafter described.

The front is flat and straight upon its lower

edge, the ends running back inclined outward. The top is curved from the ends upward, then each with a straight or flat portion, the center rising in nearly a semicircular form, and from this extending back flaring or outwardly inclined, as shown in the illustrations. This face and top are ornamented by tracery in relief upon a matted or other surface. At the ends ears are formed for the purpose of securing the pull to the drawer-front, but are no part of the design.

I claim as my invention—

The design for drawer-pull, as herein described, and as shown in the accompanying illustration.

ADOLPH WUNDER.
